(57) CLAIM

The ornamental design for patio furniture, as shown and described.

DESCRIPTION

FIG. 1 is a front perspective view of a first embodiment of the patio furniture showing the new design;

FIG. 2 is another front perspective view thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a right elevation view thereof;

FIG. 8 is a left elevation view thereof;

FIG. 9 is a front perspective view of a second embodiment of the patio furniture showing the new design;

FIG. 10 is another front perspective view thereof;

FIG. 11 is another front elevation view thereof;

FIG. 12 is another back elevation view thereof;

FIG. 13 is another top plan view thereof;

FIG. 14 is another bottom plan view thereof;

FIG. 15 is another right elevation view thereof;

FIG. 16 is another left elevation view thereof;

FIG. 17 is a front perspective view of a third embodiment of the patio furniture showing the new design;

FIG. 18 is another front perspective view thereof;

FIG. 19 is another front elevation view thereof;

FIG. 20 is another back elevation view thereof;

FIG. 21 is another top plan view thereof;

FIG. 22 is another bottom plan view thereof;

FIG. 23 is another right elevation view thereof;

FIG. 24 is another left elevation view thereof;

FIG. 25 is a front perspective view of a fourth embodiment of the patio furniture showing the new design;

FIG. 26 is another front perspective view thereof;

FIG. 27 is another front elevation view thereof;

FIG. 28 is another back elevation view thereof;

FIG. 29 is another top plan view thereof;

FIG. 30 is another bottom plan view thereof;

FIG. 31 is another right elevation view thereof; and,

FIG. 32 is another left elevation view thereof.

The broken lines in the drawings are for the purpose of illustrating portions of the patio furniture that form no part of the claimed design.

1 Claim, 20 Drawing Sheets
